CLAIM

The ornamental design for an overhead display, as shown and described.

DESCRIPTION

FIG. 1 is a front, bottom, right side perspective view of an overhead display of the new design.

FIG. 2 is a front elevation view of the overhead display of FIG. 1.

FIG. 3 is a rear elevation view thereof.

FIG. 4 is a left side elevation view thereof.

FIG. 5 is a right side elevation view thereof; and,

FIG. 6 is a bottom plan view thereof.

The broken lines in the Figures are included for the purpose of defining the claim boundary, and form no part of the claimed design.
